GEORG ZAPF, OF COLOGNE, GERMANY, ASSIGNOR TO FELTEN & GUILLEAUME CARLSWERK ACTIENGESELLSCHAFT, OF COLOGNE-MULHEIM, GERMANY

METHOD OF FINISHING THE ENDS AND FIXING ROPES

Application filed October 13, 1930, Serial No. 488,465, and in Germany November 25, 1929.

For enabling ropes, for instance bridge ropes, to be fixed, it has already been proposed to provide the ends of the ropes with heads. Hitherto this has been effected by slipping over the end of the rope a rope head made of steel, the inside of which is conical. Inside the conical part of the rope head the end of the rope is loosened to an extent corresponding to the length of the rope head and the separate wires are separated. After the separate wires have been tinned, the so-called splayed end is made, that is, the interior of the rope head in which are the separated wires of the rope end is filled with a lead alloy. The rope end, the mould is removed and for fixing the rope end a shackle preferably consisting of two parts is placed on the splayed end. The shackle is pressed firmly on the rope end by means of bolts. The shackle 55 may be so constructed that when it is screwed on, the splayed end is more firmly compressed, so that, on the load being applied to the rope for the first time, a further compression of the splayed end and a consequent slipping of the shackle is impossible. 60

The accompanying drawing shows an arrangement for carrying out the method according to the invention. Fig. 1 shows a piece of rope and the rope end seen from the side and Fig. 2 is a plan view of the rope in section and of the rope end. In both figures the rope is marked *a*. *b* is the conical part of the rope end, in and about which a suitable material is poured so as to form the splayed end. *c* and *c'* are the two halves of the shackle. The parts *c* and *c'* are pressed together by bolts *d* and nuts *e*. 65

The essential feature of the invention does not reside in the device shown in the drawing, but in the described method, and the device used in applying the method according to the invention can thus differ from that shown. Each half of the shackle can be made in two or more parts (see broken lines 70 in Fig. 1), and the shackle may be made in one part instead of in two parts. This last constructional form is indicated in Fig. 2 by the broken line shown on the right-hand half of the figure, the flanges *f*, *f'* being in this 75 case omitted.

What I claim is:

A method of finishing and securing the ends of ropes comprising spreading out the wires at the end of the rope, casting metal 90 round the spread out wires allowing the cast end to cool slowly, rapid withdrawal of heat being avoided, removing the mold and fixing a shackle consisting of several parts around 95 the end of the rope.

In testimony whereof I have signed my name to this specification.

G. ZAPF.
